UNITED STATES PATENT OFFICE.

TOWNSON HAND, OF ORLANDO, FLORIDA.

SHOE-HEEL.

1,330,183.

Specification of Letters Patent. Patented Feb. 10, 1920.

Application filed April 14, 1919. Serial No. 289,809.

To all whom it may concern:

Be it known that I, TOWNSON HAND, a citizen of the United States, and a resident of Orlando, in the county of Orange and State of Florida, have invented certain new and useful Improvements in Shoe-Heels, of which the following is a specification.

My invention is an improvement in shoe heels, and has for its object to provide a heel capable of quick and easy attachment to the heel of a shoe, the said heel being of resilient material and provided with a reinforcing plate by means of which it may be attached to the shoe, and wherein the heel body is so arranged that a maximum of cushioning effect is obtained and maximum of gripping capacity to prevent slipping.

In the drawings:—

Figure 1 is a perspective view of the heel 20 in place,

Fig. 2 is a perspective view of the attaching plate,

Fig. 3 is a similar view of the reinforcing plate,

Fig. 4 is a similar view of the bearing plate,

Fig. 5 is a vertical section through the completed heel,

Fig. 6 is a perspective view of the rivet,

Fig. 7 is a horizontal section at the reinforcing plate, of a modified construction,

Fig. 8 is a vertical section of the same,

Fig. 9 is a perspective view of one of the lugs.

In the embodiment of the invention shown in Figs. 1 to 6 inclusive, the improved heel comprises a holding plate 1 which is of circular or disk-like form, as shown, having a central opening 2, and having a series of openings 3 near its periphery. This disk is secured to the heel 4 of the shoe 5, by means of nails 6 as shown, the nails being passed through the openings 3.

The heel proper comprises a disk-like body 7 of rubber or the like, the said body being tapering as shown, having its small end approximately the same diameter as that of the plate 1, and within this body is arranged a plate 8 of metal, the said plate 50 being a reinforcing plate and being of slightly less diameter than the plate 1.

This plate 8 has a central opening 9 which is adapted to register with the opening 2, and it has a series of openings 10 through 55 which the material of the heel body 2 is

adapted to pass, and thoroughly lock the reinforcing plate to the heel body.

Referring to Fig. 5, it will be noticed that the body is concave or recessed on its top as indicated at 11, the recess extending 60 from near one side wall to near the other, and the said heel body has a central opening 12 registering with the openings 2 and 9 of the plates 1 and 8. On its undersurface and at its center, the heel body is also recessed as indicated at 13, to form a suction cavity, for insuring a firm grip of the heel body on the ground.

A bearing plate 14 is provided, the said plate being a disk as shown in Fig. 4, 70 having the central opening, and having a hub-like or tubular extension 15 at the opening. This bearing plate is adapted to abut against the plate 1 with the extension 15 in register with the opening 2, and with the 75 tubular extension passing into the opening 12 of the heel body. The parts are secured together by a rivet 16. This rivet has a head 17 which is counter-sunk on the inner surface of the insole at the heel as shown, and the rivet passes through an opening in the insole and heel, passing through the openings 2 and 9 of the plates 1 and 8, and through the opening 12 of the heel body.

Over a large portion of its length, this 85 rivet is tapering as shown at 18, and this tapering portion is adapted to extend into a sleeve 19 which is arranged within the openings 2 and 9 and in the extension 15, the said sleeve being of sufficient length to 90 pass well into the heel when the head thereof is counter-sunk in the opening 9, the said opening being reamed as shown in Fig. 5.

The end of the rivet is headed at the lower end of the sleeve as shown in Fig. 5, 95 and the parts are thus locked firmly together. In practice, the rivet is of copper. Thus the rivet does not buckle when it is being headed or when in use, and the rivet and sleeve form a firm rigid means of securing the parts together.

Referring to Fig. 5, it will be noted that only the edge of the heel body bears against the bearing plate 14, the central portions of the heel body and bearing plate being separated from each other as shown. The concavity or cup 13 provides for vacuum that will firmly grip a walk for instance and prevent slipping, and also increases the cushioning effect, absorbing shock and jar. 110

The improved heel is especially adapted for construction workers on roofs and other slippery places. In Figs. 8 and 9 the heel body 20 which corresponds with the heel body 7 of Fig. 5 has a reinforcing plate 21 corresponding with the plate 8, but wearing lugs 22 are connected with the outermost openings 10 of the plate. These lugs or plugs have reduced ends 23 which engage 10 within the openings corresponding to the openings 10, and the plugs are of such length that their free ends will be flush with the undersurface of the heel body, the plugs being buried in the material of the 15 heel body.

The reinforcing plates 8 and 21 act not only as reinforcing and stiffening plates, but serve as a means for securing the heel body to the heel. The concavity 11 in the 20 top of the heel body forms a cushion between the heel body and the bearing plate assisting in cushioning shock and jar.

I claim:—

1. A heel comprising an attaching plate 25 having means for connecting the same to the heel of a shoe, a heel body of resilient material having a central opening and having a reinforcing plate embedded in the material thereof and provided with openings, a bearing plate having a central hub and means for connecting the reinforcing plate to the attaching plate and extending 30

through the heel body and the hub, the upper face of the heel body being concave to provide a cushioning effect, said connecting means comprising a sleeve extending through the hub and through said registering openings in the attaching and reinforcing plates and a stem or rivet connected with the heel and passing through the sleeve 40 and being adapted to be headed at the outer end thereof.

2. A heel comprising an attaching plate having means for connecting it to the heel of a shoe, a heel body of resilient material 45 having a central opening and having a reinforcing plate embedded in the material thereof and provided with an opening registering with the opening of the attaching plate, a bearing plate having a central hub, and means for connecting the reinforcing plate to the attaching plate and extending through the heel body and the hub, said connecting means comprising a sleeve extending through the hub and through the 55 registering openings in the attaching and reinforcing plates, and a stem connected with the heel and passing through the sleeve and adapted to be headed at its outer end.

TOWNSON HAND.
